UNITED STATES PATENT OFFICE

95,034

DESIGN FOR A PLAY BALL

Carl K. Frederick, Detroit, Mich.

Application January 23, 1935, Serial No. 55,000

Term of patent 14 years

To all whom it may concern:

Be it known that I, Carl K. Frederick, a citizen of the United States, residing at Detroit, in the county of Wayne and State of Michigan, have invented a new, original, and ornamental Design for a Play Ball, of which the following is a specification, reference being had to the accompanying drawing, forming part thereof.

Figure 2 is an elevation looking in another direction of a play ball, showing my new design.

I claim:

The ornamental design for a play ball, as shown.

CARL K. FREDERICK.
